PUMP BODY

Robert F. Rasmussen, 3800 56th Ave. N.,
Minneapolis, Minn. 55429

Filed Mar. 25, 1970, Ser. No. 22,042

Term of patent 14 years

Int. Cl. D15—02

U.S. Cl. D65—1

FIG. 1

FIG. 3

FIG. 2

FIG. 4

FIG. 1 is a side elevational view of a pump body showing my new design, the side opposite that shown being substantially a mirror image;

FIG. 2 is a view in top plan thereof;

FIG. 3 is an end elevational view thereof as seen from right to left of FIG. 1; and

FIG. 4 is an end elevational view thereof showing the end opposite that seen in FIG. 3. The bottom thereof, not shown, is substantially devoid of ornamentation.

The dotted lines in FIG. 1, representing a pump head, are for illustrative purposes only.

I claim:

The ornamental design for a pump body, as shown and described.
